Primary Examiner — Patricia Palasik(74) *Attorney, Agent, or Firm* — Edmonds & Nolte, P.C.(57) **CLAIM**

The ornamental design for a configurable bridge plug insert for a downhole tool, as shown and described.

DESCRIPTION

FIG. 1 is a perspective view of a configurable bridge plug insert for a downhole tool;

FIG. 2 is a side plan view thereof; and,

FIG. 3 is a top plan view thereof.

The bottom is flat and unornamented.

The broken lines in the drawings depict unclaimed environmental subject matter.
